The ornamental design for an electronic stethoscope, as shown and described.

DESCRIPTION

FIG. 1 is a bottom, left side perspective view of an electronic stethoscope showing my new design;

FIG. 2 is a bottom side plan view thereof;

FIG. 3 is a top side plan view thereof;

FIG. 4 is a right side elevation view thereof;

FIG. 5 is a left side elevation view thereof;

FIG. 6 is a front side view thereof;

FIG. 7 is a back side view thereof;

FIG. 8 is back side perspective elevation view;

FIG. 9 is the right side elevation view in FIG. 4 with a cross-section line 10-10 through the tapered portion; and, FIG. 10 shows the outer shape of the tapered portion at cross-section line 10-10 in FIG. 9.

The dot-dash lines within the inner perimeter of the FIG. 10 view show the limits of the depiction of the interior cross-section. The dot-dash lines and area within form no part of the claimed design.

The broken lines shown in the drawings depict portions of the electronic stethoscope that form no part of the claimed design.
